RAILWAY SWITCH CONTROLLING
APPARATUS

Frank H. Nicholson, Edgewood, Pa., assignor to
The Union Switch & Signal Company, Swiss-
vale, Pa., a corporation of Pennsylvania

Application May 27, 1932, Serial No. 613,955

4 Claims. (Cl. 246—29)

My invention relates to railway switch controlling apparatus, and particularly to apparatus of the type comprising means located on a vehicle and arranged to cooperate with means located in the trackway for controlling a switch. 5

I will describe one form of apparatus embodying my invention, and will then point out the novel features thereof in claims.

In the accompanying drawing, Fig. 1 is a diagrammatic view showing one form of trackway apparatus embodying my invention. Fig. 2 is a diagrammatic view showing one form of train-carried apparatus suitable for cooperation with the trackway apparatus illustrated in Fig. 1 and 15 also embodying my invention.

Similar reference characters refer to similar parts in each of the views.

Referring first to Fig. 1, the reference character 1 designates a stretch of railway track which 20 is divided by insulated joints 2 to form track sections D—E, E—Q and Q—F. Located in the section Q—F is a railway switch A by virtue of which traffic moving in the direction indicated by the arrow will proceed on the main track 1 when the 25 switch is in its normal position, and will be diverted to a branch track 3 when the switch is in its reverse position.

Each track section is provided with a track circuit including a battery 35, and a track relay 30 designated by the reference character T with a distinguishing suffix.

Switch A is operated by an electric motor M through the medium of a suitable mechanism which is represented by the dash line 34. This 35 motor is controlled by a polarized relay L having a normal winding 6 and a reverse winding 7. As shown in the drawing, the normal winding 6 is energized so that the polar contacts of relay L are swung to their normal positions; the switch 40 A is likewise in its normal position and motor M is deenergized. Assuming now that normal winding 6 becomes deenergized and reverse winding 7 becomes energized, the polar contacts of relay L will be swung to their right-hand or 45 reverse positions. Motor M will then be operated in such direction as to reverse the switch A, the circuit being from terminal B of a suitable source of current, through polar contact 26 in its right-hand position, motor armature 27, polar contact 50 28 in its right-hand position, contact 29 operated by the switch and open only when the switch is in its reverse position, and motor field winding 30 to terminal C of the same source of current. When the switch A reaches its reverse position 55 this motor circuit will be opened at contact 29.

If now relay L is restored to its normal position wherein contacts 26 and 28 are returned to their left-hand positions, motor M will be operated to restore switch A to its normal position, the circuit being from terminal B through contact 28, 5 motor armature 27, contact 26, contact 31 which is operated by the switch and is open only when the switch occupies its normal position, and motor field winding 30 to terminal C. When the switch reaches the full reverse position this circuit will be opened at contact 31.

Associated with track relay TD is a repeater relay G, the circuit for which includes front contact 8 of relay TD, so that relay G will be energized or deenergized according as relay TD is 15 energized or deenergized.

The reference character H designates a normally deenergized time measuring device provided with a circuit which includes back contact 12 of relay G, so that this time measuring 20 device is set into operation when a train enters section D—E. After a fixed interval of time following the energization of this device H, its front contact 14 will close.

Located at a suitable point in section D—E, 25 and preferably very close to the exit end of this section, is a light responsive device P, which may, for example, be a photoelectric cell. Referring to Fig. 2, the reference character V designates a vehicle or train travelling on the track rails 1 30 and provided with a source of light W arranged to project light rays upon the trackway cell P just before the train passes out of section D—E. This source of light is provided with a circuit including a battery 32 and a normally open contact U which may be closed manually by the 35 engineer. Preferably the source W is provided with a reflector 33 to direct an intense beam of light upon the trackway cell P.

Located in the trackway is a control relay K 40 having a pick-up winding 4 and a holding winding 5. The pick-up winding 4 is provided with a circuit which passes from a battery 15 through the photo cell P, front contact 13 of track relay TE, contact 14 of the time element device 45 H, and winding 4 to battery 15. The parts of this circuit are so arranged that relay K is normally deenergized, but becomes effectively energized to close its front contacts when and only when light from the train carried source W 50 strikes the photocell P. The circuit for the holding winding 5 of relay K is from terminal B, through the back point of contact 9 of relay G, front contact 16 of track relay TE, front contact 17 of relay K, and winding 5 to terminal C. It 55

follows, therefore, that when relay K has once been effectively energized and section Q-F remains unoccupied, this relay will remain energized until the entire train passes out of section 5 D-E, that is, until relay G again becomes energized.

The normal winding 6 of the polar relay L is provided with a circuit which passes from terminal B, through the front point of contact 9 of relay G, front contact 9a of relay TE, front contact 10 of relay TF, back contact 11 of relay K, and winding 6 to terminal C. The reverse winding 7 of polar relay L is provided with a circuit which passes from terminal B, through front contact 18 of track relay TF, front contact 19 of relay K, and winding 7 to terminal C.

Located at the entrance end of section Q-F is a high speed signal SH and a low speed signal SL, the first or the second of which signal 20 indicates proceed, according as switch A is in the normal or the reverse position, assuming that track section Q-F is unoccupied. The circuit for the high speed signal SH is from terminal B, through a contact 20 operated by switch A 25 and closed only when the switch is in the normal position, front contact 21 of track relay TF, back contact 22 of relay K, and signal SH to terminal C. The low speed signal SL is provided with a circuit which passes from terminal B, 30 through front contact 23 of relay K, contact 24 operated by switch A, and closed only when the switch is in the reverse position, front contact 25 of track relay TF, and signal SL to terminal C.

35 The time element characteristic of the device H and the location of the cell P in section D-E are such that contact 14 of the device H will not be closed when the train reaches cell P unless the train is travelling at less than a given 40 speed, so that a high speed train can not reverse switch A.

The operation of the apparatus is as follows: As illustrated in the drawing, switch A is in its normal position, and all other parts of the apparatus are in the positions corresponding to 45 this position of the switch. High speed signal SH indicates proceed. Assuming now that a train moving toward the right enters section D-E and is travelling at less than the speed limit referred to hereinbefore, contact 14 of relay H will close before the train-carried light source W reaches the cell P. If the contact U is closed when the source W passes cell P, relay K will become energized, thereby opening at contact 11 the circuit for the normal winding 6 of 50 relay L and closing at contact 19 the circuit for the reverse winding 7 of this relay. Switch A will then be reversed, signal SH will indicate stop, and signal SL will indicate proceed. The 55 train will then be diverted from the main track 1 to the branch track 3. After the rear end of the train passes insulated joint 2 in the branch track 3, track relay TF will close, and since relay G has in the mean time become energized and relay K deenergized, the reverse winding 7 of relay L will be deenergized and the normal winding 6 will again become energized. Motor M will, therefore, be operated to return switch A to its normal position.

70 If the train is to continue on the main track 1, the engineer takes no action upon passing the photocell P, so that switch A will remain in its normal position. The high speed signal SH will change to the stop indication when the train enters section Q-F and will return to the pro-

ceed indication when the train leaves this section.

The purpose of the second approach section E-Q, is to open the circuit for the pick-up winding 4 of relay K immediately after a train 5 has passed the photocell P. Assuming, therefore, that section E-Q is occupied by a first train which has not caused switch A to reverse, a second train passing through section D-E can not reverse the switch, because the circuit for the 10 pick-up winding 4 of relay K will be open at contact 13 of track relay TE. Of course, if the first train has proceeded into section Q-F and the second train causes relay K to become energized, this operation will have no effect on the 15 switch A because the circuit for reverse winding 7 of relay L will be open at front contact 18 of track relay TF.

Although I have referred to the element W on the train as a source of light, it is understood 20 that this term is to be given its broadest significance, namely, that the device W is a source of radiant energy, and that it may, therefore, emit light within the visible spectrum, or that it may emit radiant energy beyond the visible spectrum 25 either in the ultra-violet or the infra-red direction. In any event the photocell P is designed to respond to the particular type of energy emitted by the source W.

Although I have herein shown and described 30 only one form of apparatus embodying my invention, it is understood that various changes and modifications may be made therein within the scope of the appended claims without departing from the spirit and scope of my invention.

Having thus described my invention, what I claim is:

1. In combination, a stretch of railway track provided with a switch and with a track circuit including a track relay in the rear of the switch, a repeater relay controlled by a front contact of said track relay, a slow pick-up relay controlled by a back contact of said repeater relay, a control relay having a pick-up winding and a stick winding, a train carried source of light, a circuit for said pick-up winding including a front contact of said slow pick-up relay and a photocell located in the limits of said track circuit, said pick-up circuit being so adjusted that the control relay 45 can be effectively energized when and only when said cell is exposed to light from said train carried source, a circuit for said stick winding including a front contact of the control relay and a back contact of said repeater relay, and means for reversing said switch when and only when said control relay is energized.

2. In combination, a stretch of railway track provided with a switch and with a track circuit located in the rear of the switch, a photocell located within the limits of said track circuit, a train carried source of light, a normally deenergized control relay, a time element device set into operation when a train enters said track circuit, a pick-up circuit for said control relay closed only when said cell is exposed to light from said source and said time element device has completed its operation, the time characteristic of said device and the location of said cell in the track circuit being such that the relay can not be energized unless the train is moving at less than a given speed, a stick circuit for said relay closed when the relay is energized and said track circuit is occupied, and means for reversing said switch when said control relay is energized.

3. In combination, a stretch of railway track provided with a switch and with a track circuit located in the rear of the switch, a photocell located within the limits of said track circuit, a train carried source of light, a normally deenergized control relay, a pick-up circuit for said relay closed only when said track circuit is occupied and said cell is exposed to light from said source, a stick circuit for said relay closed when the relay is energized and said track circuit is occupied, means for reversing said switch when said control relay is energized, a high speed signal and a low speed signal for said switch, means for clearing said high speed signal when and only when said relay is released and the switch is in normal position, and means for clearing said low speed signal when and only when said relay is energized and the switch is in reversed position.

4. In combination, a main section of railway track containing a switch, a second section in the rear of said main section, a relay, means for operating said switch to one position or the other according as said relay occupies its normal or its reverse position, a first circuit for operating said relay to its normal position, means effective when said main section and said second section are both unoccupied for closing said first circuit, a second circuit for operating said relay to its reverse position, and means including cooperating train carried and trackway elements for at times closing said second circuit when said second section is occupied and said main section is unoccupied.

FRANK H. NICHOLSON.
